UNITED STATES PATENT OFFICE.

JOHN W. HENRY, OF CRAWFORDSVILLE, INDIANA.

WEATHER-STRIP.

SPECIFICATION forming part of Letters Patent No. 736,392, dated August 18, 1903.

Application filed January 21, 1903. Serial No. 139,975. (No model.)

To all whom it may concern:

Be it known that I, JOHN W. HENRY, a citizen of the United States, residing at Crawfordsville, in the county of Montgomery and State of Indiana, have invented a new and useful Weather-Strip, of which the following is a specification.

This invention relates to that class of weather-strips attached to the bottoms of doors and operated by the opening and closing of the door for excluding air and moisture, and has for its object the production of a device of this character simple in construction, easily applied, and which will engage the door or holding-strip at one point and the carpet strip or sill at another, so that the joints between the parts will be effectually closed.

Another object of the invention is to produce a device of this character which will be maintained normally in an inoperative position when the door is open, and thus obviate unnecessary friction.

Other novel features of the invention will be disclosed in the annexed specification and be specified in the claims following.

In the drawings illustrative of the invention, in which corresponding parts are denoted by like characters of reference, Figure 1 is a perspective view of a portion of a door-frame and door with the improvement applied. Fig. 2 is a rear elevation of the device detached, illustrating the manner of constructing and applying the operating-spring. Fig. 3 is an enlarged transverse section with the packing-strip closed, and Fig. 4 is a similar view with the packing-strip open or out of action.

The improved device may be applied to any form of outside door, and for the purpose of illustration it is shown applied to an ordinary door and its frame, the door indicated at 10, the side members of the frame at 12 12, and the carpet-strip at 13.

The improved device consists of a supporting member 14, secured across the door 10 near its bottom edge and provided with a longitudinal recess 15 contiguous to the door, as shown in Figs. 3 and 4.

Attached by hinges 16 to the member 14 is a packing-strip 17, one edge of the packing-strip having the flexible packing 18, of rubber

or other similar suitable material, and the other edge, 19, formed concentric to the hinges 16 and movable in constant engagement with the adjacent face of the door 10, so that no matter in what position the packing-strip may be placed the inner edge of the strip will engage the door and effectually shut off the passage of air or moisture at that point, while the flexible strip 18 will shut off the passage at the opposite edge. The leaves of the hinges 16 will be embedded both in the supporting-strip 14 and the packing-strip 17, so that the packing-strip will be maintained in constant contact with the lower surface of the strip 14.

The packing-strip 17, with its yieldable portion 18, closes against the carpet-strip 13 when operated by the door; but when the door is opened the packing-strip will be maintained in its elevated or inoperative position.

The means for operating the packing-strip is a spring, preferably of the "torsional" variety, as shown at 20 in Figs. 2, 3, and 4, and will exert its force to hold the packing-strip in its elevated or inoperative position, as above noted.

Attached to the frame member 12 is a stop 21 in position to be engaged by the strip 17 when the door is closed to throw the strip 18 downward with its flexible packing 18 in contact with the carpet-sill, the rear edge 19 at the same time remaining in constant engagement with the door and the upper side thereof in contact with the strip 14, as above noted. By this simple arrangement no gap will at any time be left between the strip 17 and the strip attached to the door or between the sill or carpet-strip and the packing-strip when the door is closed, as the concentric edge 19 and the contact of the strips 14 and 16 shuts off all circulation upon one side and the flexible packing 18 shuts off the circulation upon the other side, as will be obvious by reference to Fig. 3. This produces a very simple easily applied device which is efficient for the purpose intended and operates automatically by the closing of the door and which may be applied to any door and adjusted to fit inequalities and irregularities of the carpet strip or sill.

The parts may be of any suitable material, either wood or metal, or partially of wood and partially of metal, as may be preferred.

Having thus described my invention, what I claim is—

1. A weather-strip consisting of a supporting member having a longitudinal recess contiguous to the door, a packing-strip intermediate hinged to said supporting member and foldable by one edge into said recess with the foldable edge concentric to said hinges and operating in constant engagement with the contiguous face of the door, a spring disposed to maintain said packing-strip normally in an inoperative position, and a stop adapted to close said packing-strip into operative position when the door is closed.
- 15 2. The combination of a door, a supporting member having a longitudinal recess contiguous to the door, a packing-strip intermediate hinged to said supporting member and

foldable by one edge into said recess with the foldable edge concentric to said hinges and operating in constant engagement with the door, and its hinged portion in constant engagement with the supporting member, a spring operating to maintain said packing-strip normally in an inoperative position, and a stop in the path of said packing-strip and adapted to close it into operative position when the door is closed.

In testimony that I claim the foregoing as my own I have hereto affixed my signature in the presence of two witnesses.

JOHN W. HENRY.

Witnesses:

C. L. HENRY,
O. H. HUTCHINGS.
